UNITED STATES PATENT OFFICE.

ARTHUR TREVOR DAWSON AND GEORGE THOMAS BUCKHAM, OF WESTMINSTER,
LONDON, ENGLAND, ASSIGNEES TO VICKERS LIMITED, OF WESTMINSTER,
ENGLAND.

LOCK MECHANISM OF ORDNANCE.

1,337,308.

Specification of Letters Patent. Patented Apr. 20, 1920.

Application filed May 29, 1918. Serial No. 237,362.

To all whom it may concern:

Be it known that we, Sir ARTHUR TREVOR DAWSON, knight, and Sir GEORGE THOMAS BUCKHAM, knight, both subjects of the King of Great Britain, residing at Vickers House, Broadway, Westminster, in the county of London, England, have invented certain new and useful Improvements in or Relating to the Lock Mechanism of Ordnance, of which the following is a specification.

This invention relates to ordnance lock mechanism of the kind having a sliding lock frame movable transversely to the axis of the gun in a box slide attached to the rear end of the axial vent bolt.

According to the invention the slides on which the lock frame moves are formed partly on the box slide and partly on the axial vent bolt so that the lock frame, when assembled, serves to retain the box slide in its correct position on the axial vent bolt.

In order that the said invention may be clearly understood and readily carried into effect we will describe the same more fully with reference to the accompanying drawings, in which:—

Figure 1 is a rear elevation of the improved lock mechanism, the lock frame being adapted to move in a vertical path and being shown in the closed position.

Fig. 2 is a section taken approximately on the line 2, 2 of Fig. 1.

Fig. 3 is a section taken approximately on the line 3, 3 of Fig. 2, and

Fig. 4 is a section taken approximately on the line 4—4 of Fig. 1.

B is the box slide and C is the axial vent bolt to which the box slide is connected by a continuous screw thread or by interrupted collars in the usual manner. D is the lock frame, D' is a lock frame operating handle pivoted at d' to a bracket D^x attached to the lock frame, and d' is a hook-shaped projection on the handle D' for engaging in a recess b' in the box slide to hold the lock frame in the closed position. E is the firing hammer pivoted at e to the lock frame so as to move in a plane at right angles to the path of travel of the lock frame and E^x is a projection on the hammer E with an inclined surface on which projection an extension D^y of the handle D' engages to retract the hammer when the handle is rocked about its pivot to disengage the projection d' from

its recess b' prior to moving the lock frame to the open position.

The lock frame D is formed with longitudinal grooves D², D² adapted to engage with fins B², B² on the box slide B and also with fins C², C² on the axial vent bolt the latter 60 fins forming continuations of the fins B², B². In this manner the lock frame serves as aforesaid to retain the box slide in its correct position on the axial vent bolt.

What we claim and desire to secure by Letters Patent of the United States:—

1. In ordnance lock mechanism, the combination with the mushroom stem or axial vent bolt and the receiver or box slide attached thereto, of a wedge or lock frame 70 movable while in engagement with both the axial vent bolt and the box slide, and means whereby said lock frame by its said engagement directly forms a connection between the axial vent bolt and the box slide to prevent the latter from moving angularly on said bolt.

2. In ordnance lock mechanism, the combination with the mushroom stem or axial vent bolt and the receiver or box slide attached thereto, of a sliding wedge or lock frame adapted to slide while in engagement with both the axial vent bolt and the box slide, and means whereby said lock frame by its said engagement directly forms a connection between the axial vent bolt and the box slide to prevent the latter from moving angularly on said bolt.

3. In ordnance lock mechanism, the combination with the mushroom stem or axial vent bolt and the receiver or box slide attached thereto, of a sliding wedge or lock frame movable transversely to the axis of the gun in said box slide and guides on the axial vent bolt with which the lock frame 95 slidably engages to prevent angular movement of the box slide on the said bolt.

4. In ordnance lock mechanism, the combination with the mushroom stem or axial vent bolt and the receiver or box slide attached thereto, of a sliding wedge or lock frame having longitudinal grooves, and fins on the box slide and on the axial vent bolt with which said grooves engage to prevent angular movement of the box slide on the 105 said bolt.

5. In ordnance lock mechanism, the combination with the elements claimed in claim

1, of a lock frame operating handle engaging with part of the box slide when the lock frame is in the closed position to hold the latter in this position.

5 6. In ordnance lock mechanism, the combination with the elements claimed in claim 1, of a lock frame operating handle pivoted to the lock frame and a projection on this

handle for engaging in a recess in the box slide to hold the lock frame in the closed position. 10

In testimony whereof we affix our signatures.

ARTHUR TREVOR DAWSON.
GEORGE THOMAS BUCKHAM.
